UNITED STATES PATENT OFFICE

MILLARD J. HAMNER, OF CLEVELAND, OHIO, ASSIGNOR TO GENERAL ELECTRIC COMPANY, A CORPORATION OF NEW YORK

ELECTRIC LAMP

Application filed May 22, 1925. Serial No. 32,193.

My invention relates to improvements in electric lamps and more particularly to gas-filled lamps of the type disclosed in the Langmuir United States Patent 1,180,159, issued

5 April 18, 1916.

In a gas-filled electric lamp, which is ordinarily mounted base upward, the base and contiguous parts are heated considerably by convection currents which rise from the filament region. It has been customary in some cases to provide a disc deflector to break up such currents and to protect the base of the lamp from them. My invention comprises such a deflector and an effective means of 10 mounting it.

My invention is illustrated in the accompanying drawings in which Fig. 1 is an elevation of a gas-filled electric incandescent lamp in which it is embodied; Fig. 2 is a plan in 20 section along the line 2-2 of Fig. 1; and Fig. 3 is an enlarged plan of the deflector or shield.

The lamp illustrated in Fig. 1 comprises a bulb 10 having a comparatively short neck 11 which is provided at its upper end with a base 12. Within the bulb there is a stem 13 which has sealed therein the leading-in wires 14-15. The customary method of sealing in these leading-in wires is to extend them 25 through the stem tube, to fuse the inner end of the stem tube and to compress by clamping the fused glass around the said wires. This results in a flat solid mass of glass 16 at the inner end of the stem tube. Integrally united 30 to the stem tube 13 is an arbor 17 usually of glass which has supports 18 sealed therein which engage the filament 19. Current is supplied to the filament 19 through the conductors 20-21 which are connected to the 35 leading-in wires 14 and 15.

As hereinbefore stated, the lamp illustrated is of the gas-filled type and in order to prevent the hot gas from rising up into the neck portion 11 of the bulb 10, I provide a 40 shield or deflector 22. The shield or de-

flector is preferably made of metal and, as shown in Figs. 2 and 3, comprises a pair of semi-circular stampings 23-24 recessed at 25-26 so as to conveniently fit about the clamped portion 16 of the stem tube 13. The 50 stampings 23-24 are attached to the clamped portion 16 by means of the pointed tabs 27-28 extending from the members 23-24 and forming an integral part thereof. The assembly of the stampings 23-24 may take 55 place during the manufacture of the stem. This permits the tabs 27-28 to be inserted immediately after the fused portion has been clamped at which time the glass is still in a semi-plastic condition.

After the stampings 23-24 have been assembled and attached to the clamped portion 16, as shown in Fig. 2, they form a disc having a vent 29 therein allowing a certain amount of the hot gas to pass therethrough. 65 This is of advantage as it prevents an overheating of the members 23-24 and also allows a certain amount of the vaporized filament material to deposit on the stem and in the upper neck portion where discoloration is comparatively harmless.

What I claim as new and desire to secure by Letters Patent of the United States, is:

1. In an electric lamp, the combination 75 of a bulb, a stem sealed to said bulb, leading-in conductors extending through and sealed in a clamped portion of said stem and a deflector located in a plane substantially transverse to the axis of said stem and comprising a plurality of disc members each having a portion sealed in said clamped portion of said stem.

2. In an electric lamp, the combination 80 of a bulb, a stem sealed to said bulb, leading-in conductors extending through and sealed in the end portion of said stem and a deflector comprising a plurality of disc members each located in substantially the same plane and having a portion extending into said leading- 85

45 shield or deflector 22. The shield or deflector 22 being of metal and having a pair of semi-circular stampings 23-24 recessed at 25-26 so as to conveniently fit about the clamped portion 16 of the stem tube 13.

in wire seal portion of said stem and having a space therebetween.

3. In an electric lamp, the combination of a bulb, a stem sealed to said bulb, leading-in conductors extending through and sealed in a clamped portion of said stem and a deflector comprising a pair of disc members located in substantially the same plane one supported on each side of said stem and having a space therebetween.

10 In witness whereof, I have hereunto set my hand this 19th day of May, 1925.

MILLARD J. HAMNER.
